SUN MASK

Frances A. Rentchler, Mamaroneck, N. Y.

Application December 30, 1935, Serial No. 56,644

1 Claim. (Cl. 2—12)

This invention relates to an eye shield of the general nature of a mask for protecting the eyes of a user from sun glare or the like.

More particularly, the present invention relates to an eye protecting mask having water resistant attributes, and thus is adapted for use in many types of sports as for instance swimming, inclusive of beach wear, skiing, and like activities.

10 The present invention has as its primary objects the provision of a shield for the eyes that will:—

1. Minimize the glare of sunlight or other brilliant light, direct and/or reflected, while still

15 permitting adequate vision;

2. Provide a comfortable fit over the eyes only of the user thereby to prevent unsightly portions on the face as it becomes gradually tanned after long, continued use at the seashore;

20 3. Employ in its manufacture material which is substantially indestructible during use of the device;

4. Be adaptable for embodiment in a wide variety of ornamental forms harmonizing in color 25 and configuration with the costumes worn in various sport and like activities;

5. Possess physical characteristics capable of 30 withstanding strenuous use in sport and the like activities, inclusive of exposure to the elements, such as water, wind, snow, etc.

Embodiments of the present invention are 35 preferably wholly water resistant, flexible, and substantially indestructible during use, and for this purpose may be formed from sheet rubber, rubberized fabric, or the like. Such embodiments are therefore adapted for beach wear or for wear when the user is exposed to the elements, as while skiing or engaging in like outdoor activities.

40 The device comprises a mask-like portion including two eye members integrally interconnect- 45 ed by a nose bridge. Each eye member is con-figured to conform to an eye socket of a wearer of the device, being concavo-convex to provide for eyelash extension and movement, the defining edges of the concavo-convex formation being adapted to engage the face of the wearer of the device proximate the eyebrows and the cheek bones. The mask-like portion is secured in place 50 by suitable fastening means, as for instance by a strap or cord encircling the upper part of the head. Desirably the mask-like portion is contoured according to the general formation of the part of the head around which it is to fit, and 55 further, has eye openings therein for affording

adequate visibility therethrough with a minimum exposure of the eyes to the direct and/or reflected rays of the sun or other source of glare, the openings for such purpose being in the form of narrow slits or the like. 5

Further features and objects of the present invention will be apparent from the following detailed description and the accompanying drawing in which:

Fig. 1 shows one embodiment of the invention 10 in place over the eyes of a user engaged in outdoor activity, such as swimming.

Fig. 2 is a front elevation of the embodiment shown in Fig. 1 on an enlarged scale.

Fig. 3 is a vertical section taken on the line 15 3—3 of Fig. 2, shown applied in use.

Fig. 4 is a detail front elevation of another embodiment of the present invention.

Referring to the drawing, and particularly to Figs. 1, 2, and 3, at 10 is shown a sun-mask or 20 eye-shield, embodying features of the present invention. The sun-mask or eye-shield 10 is indicated as formed of a material resistant to water and having the qualities of flexibility or pliability, and toughness, and yet having sufficient body 25 to retain substantially its original configuration imparted in the production of the device. Preferably the material employed is sheet rubber, or rubberized fabric of sufficient thickness and proper pliability and/or flexibility to impart the 30 desired permanence of structure and also comfort to the user.

The material may be cut to provide an integral blank having a contour of the nature of an eye-mask, and including means for retaining the 35 completed article in place on the face of the user.

The mask-like portion preferably takes the shape illustrated having the eye members 11 and 12 connected by the nose bridge 13; the members 11 and 12 are of an area sufficient to cover 40 the eye sockets of a wearer of the device, and are limited in extent proximate the eyebrows and the cheek bones.

The holding means may comprise the straps 45 14 and 15, extending integrally from respective lateral sides of the mask portion.

The blank may then be subjected to a vulcanizing forming treatment to shape it in accord with the general contour of the facial area, at the location of application of the device, advanta- 50 geously during this forming operation the bulge formation 16, Fig. 3, is provided in each of the cover members 11 and 12, to accommodate the mask to eyelash extension, and to the movements of the eyelash while opening and closing the eyes. 55

In the stage of final assembly, fastening means, such as a two part snap fastener 17 having the component elements 17a and 17b, for securing and positioning the respective free ends of the straps 14 and 15, are attached. Also, adjustability for varying head sizes may be had by provision of an adjusting means of any suitable type, such as the buckle and strap arrangement shown at 18.

10 Openings of desired total area, configuration, slat, etc., are so positioned in the eye members 11 and 12 as to be in convenient registry with the eyes proper when the mask is in use. These openings may take a variety of forms consistent 15 with their function of affording adequate visibility therethrough while at the same time excluding a substantial quantity of the glaring rays of light. The slits 19 and 20, shown in Fig. 2, serve as an example of a practical type of light 20 opening, indicating extent of total area, configuration, slant and/or location of openings relative to the eye center, etc.

In Fig. 4 is illustrated another embodiment of the invention wherein the mask portion 21 of the 25 device formed, as before described, is retained in position when in use, by holding means such as elastic cord 22, shown separably attached thereto. Such cords 22 may extend continuously from one 30 side of same to the other, the elasticity of the cords allowing for varying head sizes. The slits 23, in the embodiment shown in Fig. 4 are another example of the shape, size, location, etc. of openings of practical advantage.

Due to the inherent nature of the material that 35 may be used in embodiments of my invention, a wide range of decorative effects may be attained in connection with sport attire or the like in addition to the distinctly practical advantages resulting from water and weather resisting attributes while the device is performing the primary 40 function of protecting the eyes of the user from the glare of the sun during outdoor activities.

Essential features of the invention may be had

in a variety of embodiments with respect both to the material used and to the structural characteristics of the resulting device, the embodiments heretofore set out being merely specific examples of preferred forms.

5 Thus, a normally transparent material such as a cellulose acetate plastic in sheet form might be utilized for the mask-like portion of the device, the same being, rendered translucent or opaque, as for instance by impressing color and/or ornamental design, thereon, except for areas corresponding to the slits 19 and 20 as in Fig. 2, or the slits 23 as in Fig. 4, or their equivalent, which are retained in a transparent state to provide the desired degree of visibility.

10 Whereas, I have described my invention by reference to specific forms thereof, it will be understood that many changes and modifications may be made without departing from the spirit of the invention as defined in the following claim.

15 I claim:

A device for shielding the eyes, comprising a mask-like portion having two eye members and a nose bridge integral with the two eye members and interconnecting the same, each of said eye 25 members being configured to substantially conform to an eye socket of the wearer for shielding the eye with a minimum of facial coverage, and further being concavo-convex to engage, along its edges, the face of a wearer proximate the eye-brows and the cheek-bones and for affording clearance for eyelash extension and movement; the said mask-like portion consisting of wholly integral, flexible, water resistant material; slit 30 openings, very small in total area compared to the total area of the eye members, disposed in the respective eye members for registry with the eyes of a wearer; and means for securing the mask-like portion in place over the eyes of a 35 wearer.

40 FRANCES A. RENTCHLER.
